UNITED STATES PATENT OFFICE.

HERMAN F. W. HUEG, OF LONG ISLAND CITY, NEW YORK.

DESIGN FOR A MOLD FOR BAKERS, &c.

SPECIFICATION forming part of Design No. 25,792, dated July 21, 1896.

Application filed June 2, 1896. Serial No. 594,048. Term of patent 7 years.

To all whom it may concern:

Be it known that I, HERMAN F. W. HUEG, a citizen of the United States, residing in Long Island City, county of Queens, and State 5 of New York, have invented and produced a new and original Design for Bakers' and Confectioners' Molds for Production of Ornamental Wares, of which design the following is a specification, reference being had to the accompanying drawing, representing the design and a sectional view of the mold.

The design of the mold is arranged in a rectangular plane, the curves and lines of which my design is composed being produced 15 in the shape of semicircular grooves.

The main features of my design are combinations of scrolls, consoles, and volutes arranged symmetrically on each side of the center line of the mold. Scrolls *a* are wider 20 apart at their base and form an approximate triangle, over whose apex is placed the volute *b*. Consoles *c* are formed on each side of the upper part of the triangular figure. Within the triangle is formed a series of concentric 25 circles *d*, and below these circles is set, appearing as a support for the central figure, a thimble-shaped stool *e*, and below this stool is set a hemispherical terminus *g*.

In each of the corners of the mold is arranged a series or string of hemispherical 30 beads *j*, those in the two lower corners being

arranged along a right angle, while those in the two upper corners are arranged along the arc of a circle.

Between the upper volute *b* and the consoles *c*, and also under the upper end of these consoles *c*, are scalloped the drop of tear shaped figures *h* and *i*, the latter being somewhat curved, and just between the upper outward curves of the two scrolls *a* a figure *k* is 35 formed of three of these drops or tears, arranged as though springing out from a series of small spheres. Below this figure *k* and within the triangle formed by the scrolls *a* and above the circles *d* is another figure, 40 45 formed of a small drop *l*, placed in the center, and two figures *m*, evolved from the drop. Below the consoles *c* and beside the scrolls *a* are scrolls *n*, with volutes branching off therefrom. 50

I claim and desire to secure by Letters Patent—

The design for a baker's and confectioner's mold as herein shown and described.

In witness that I claim the design described 55 in the foregoing specification I have signed my name in the presence of two subscribing witnesses.

HERMAN F. W. HUEG.
